UNITED STATES PATENT OFFICE

2,227,883

CALIPER

Edwin O. Grobe, Los Angeles, Calif.

Application March 27, 1939, Serial No. 264,456

3 Claims. (Cl. 33—163)

This invention appertains to new and useful improvements in calipers, the principal object being to provide a gauge for machinists, die makers, and other skilled mechanics which will be found 5 to be of high value from the standpoint of ease of operation and precision in execution.

Another important object of the invention is to provide a gauge of this character which has an unusual length which permits its use at exceptional depths.

Other objects and advantages of the invention will become apparent to the reader of the following specification.

In the drawings:

15 Figure 1 represents a side elevational view. Figure 2 is a section on the line 2—2 of Figure 1. Figure 3 is a section on the line 3—3 of Figure 1. Figure 4 is a fragmentary detailed sectional view through the lower portion of the gauge.

20 Figure 5 is a sectional view on the line 5—5 of Figure 4.

Figure 6 is a fragmentary detailed sectional view on the line 6—6 of Figure 4.

25 Figure 7 is a fragmentary side elevational view of the stationary anvil.

Referring to the drawings wherein like numerals designate like parts, it can be seen that numeral 5 represents the gear case which has the smooth opening 6 in one side and the threaded 30 opening 7 in its opposite side. The threaded opening 7 receives the threaded portion 8 of the hollow stationary anvil 9, the outer portion of which is closed while its inner end portion is open and provided with the smooth peripheral portion 10 which forms a bearing for the bevelled 35 gear 11 (see Figure 4).

The bevelled gear 11 is internally threaded and receives the elongated threaded portion 12 of the movable anvil 13, the outer end portion of which 40 is provided with a smooth periphery.

A sleeve 14 encases that portion of the movable anvil 13 located within the gear case 5, one end of this sleeve 14 being reduced as at 15 to fit 45 in the opening 6.

The sleeve 14 has an opening 16 in the top portion thereof for receiving the lock pin 16. This lock pin extends downwardly through the barrel 17 and has its lower end tapered to not only engage through the opening 16 in the sleeve 14, but also to project into the longitudinal groove 18 of the movable anvil 13.

Numerals 19 denotes the stationary barrel the lower end of which is threaded engaged as at 50 20 into the upper portion of the case 5. A bear-

ing or bushing member 21 is interposed between the lower portion of the barrel 17 and the stationary barrel 19 and the lower end of the barrel 17 carries the bushing 21 and the beveled gear 22 pressed into the barrel 17 leaving an opening in 5 the gear to receive the lock pin 16.

The upper portion of the stationary barrel 19 has the knurled hand grip portion 23 and a knurled cap 24 at its upper end through which the rotatable barrel 17 is disposed. The upper 10 portion of the rotatable barrel 17 has a knurled portion 25.

The upper end portion of the pin 16 has the knurled portion 26 and the threaded portion 27 threadedly disposed through the upper end portion 15 of the barrel 17.

Obviously, by rotating the barrel 17 adjustment of the movable anvil 13 will take place without rotation thereof, and a slight rotation of the pin 16 by its knurled end portion 26 will serve to 20 lock the anvil against further movement.

While the foregoing specification sets forth the invention in specific terms, it is to be understood that numerous changes in the shape, size and materials may be resorted to without departing 25 from the spirit and scope of the invention as claimed hereinafter.

Having described the invention, what is claimed as new is:

1. In a micrometer, a tubular barrel, a hollow 30 nipple extending from one end of the barrel and forming a casing, a tubular fixed anvil extending diametrically from one side of said casing and partway thereinto, a bearing sleeve fixed in said casing coaxially with said anvil in spaced relation thereto and opening onto the other side of the casing, a distance pin endwise movable into said anvil and sleeve and extending out of said other side of the casing, and means to move said pin comprising a tubular shaft rotatably mounted 35 in said barrel to extend at one end out of the same for manipulation thereof, a beveled gear in said casing to which said shaft is operatively connected, and a second beveled gear threaded onto said pin in the space between said anvil and 40 sleeve and confined therebetween.

2. In a micrometer, a tubular barrel, a hollow nipple extending from one end of the barrel and forming a casing, a tubular fixed anvil extending diametrically from one side of said casing and 50 partway thereinto, a bearing sleeve fixed in said casing coaxially with said anvil in spaced relation thereto and opening onto the other side of the casing, a distance pin endwise movable in said anvil and sleeve and extending out of said other 55

side of the casing, means to move said pin comprising a tubular shaft rotatably mounted in said barrel to extend at one end out of the same for manipulation thereof, a beveled gear in said casing to which said shaft is operatively connected, a second beveled gear threaded onto said pin in the space between said anvil and sleeve and confined therebetween, and means to lock said pin against endwise movement comprising a rod extending through said shaft and manipulative from the outer end of the shaft into and from locking relation to said pin.

3. In a micrometer, a tubular barrel, a hollow nipple extending from one end of the barrel and forming a casing, a tubular fixed anvil extending diametrically from one side of said casing and partway thereinto, a bearing sleeve fixed in said casing coaxially with said anvil in spaced relation thereto and opening onto the other side of the

casing, a distance pin endwise movable in said anvil and sleeve and extending out of said other side of the casing, means to move said pin comprising a tubular shaft rotatably mounted in said barrel to extend at one end out of the same for manipulation thereof, a beveled gear in said casing to which said shaft is operatively connected, a second beveled gear threaded onto said pin in the space between said anvil and sleeve and confined therebetween, and means to lock said pin against endwise movement comprising a rod extending through said shaft and manipulative from the outer end of the shaft into and from locking relation to said pin, said pin having a groove therein and said rod having a locking end extending through said sleeve into said groove to prevent rotation of the pin and for locking engagement with the bottom of the groove.

EDWIN O. GROBE.
